UNITED STATES PATENT OFFICE.

PAUL T. FRANKL, OF NEW YORK, N. Y.

DESIGN FOR A CHAIR.

Application filed April 10, 1929. Serial No. 30,828. Term of patent 7 years.

To all whom it may concern:

Be it known that I, PAUL T. FRANKL, a citizen of the United States of America, residing in New York, county and State of New York, have invented a new, original, and ornamental Design for Chair, of which the following is a specification, reference being had to the accompanying drawing, forming part thereof, in which—

I claim:

The ornamental design for a chair as shown.

Dated at New York, N. Y., this 9th day of March, 1929.

PAUL T. FRANKL.
